UNITED STATES PATENT OFFICE

2,586,282

RAILWAY SURFACING, TIE SPACING, AND
TAMPING MACHINE

John T. Wren, Charleston, S. C.

Application December 18, 1948, Serial No. 65,996

1 Claim. (Cl. 254—43)

1 This invention relates to a railway surfacing, tie spacing and tamping machine.

It is an object of the present invention to provide a machine to effectively space simultaneously a large number of railway ties and which at the same time grade and tamp the ties while they are being drawn due to the friction of the ties on the grading material.

Other objects of the present invention are to provide a surfacing, tie spacing and tamping machine for use on railways which is of simple construction, easy to operate and apply to the rails, inexpensive to manufacture, and efficient in operation.

For other objects and for a better understanding of the invention, reference may be had to the following detailed description taken in connection with the accompanying drawing, in which

Fig. 1 is a plan view of the machine embodying the features of the present invention connected to the rail for operation thereupon.

Fig. 2 is a side elevational view of the machine.

Fig. 3 is a perspective view of the rail clip.

Fig. 4 is a perspective view of the anchor cable clamp.

Referring now to the figures, 10 represents ties which are to be spaced and tamped below a railway track section 11. My machine comprises rail clips 12 adapted to slidably contain a long bar 13 at the side of the rail, an anchor cable clamp 14, a cable 15 and an adjustable ratchet 16 on the cable. The cable 15 is connected to the adjusting member 13 as indicated at 17 and extends through the ratchet 16 and the anchor clamp 14. This anchor clamp 14 is formed of heavy construction and has an opening 18 for receiving the cable, a slot 19 adapted to receive the bottom rail flange and a securing screw 21 adjustable through the clamp to fix the same upon the flange of the rail. The rail is indicated at 22 and its flange is indicated at 23.

The rail clip 12 is formed of flat stock adapted to be extended beneath the rail flange and bent to have a pocket or recess 24 through which adjusting member 13 slides. The clip 12 is made secure to the rail flange by cleat 25 which is fixed by a screw 26 to the main part of the clip 12. The rail clips 12 can be connected to either side flange of the rail to extend to either one side of the same or to the other. In other words, the rail clips are reversible.

At spaced intervals on the adjusting member 13 are depending brackets 27 adapted to engage with the sides of the ties 10. The adjusting member 13 is of channel section and rigid.

With the brackets 27 engaging with a number of the ties 10, all of these ties will be simultane-

ously spaced as ratchet 16 is worked by its handle 28. The machine will space the ties equally as well on old tracks as well as upon new.

The usual method of spacing ties is by manual labor, moving the ties by means of pinch bars. It is usually necessary to have two men at two jacks to move one tie. With the present machine, to have its maximum efficiency in operation, a four man crew is required, but twenty-four ties can be moved in the same or less time than that required by two men with jacks to move one tie. There is one of these machines at each side of the track so that the ties are moved at both ends.

In pulling the ties along the road bed, the surface of the road bed is automatically and sufficiently graded and tamped due to the friction of the ties on the ground. The ties, as they are pulled, do sufficient grading and tamping so that when the jacks are removed, the track will remain level without further grading or tamping.

While various changes may be made in the detail construction, it shall be understood that such changes shall be within the spirit and scope of the present invention as defined by the appended claim.

Having thus set forth and disclosed the nature of my invention, what is claimed is:

A railway surfacing, tie spacing and tamping machine comprising rail clips adapted to be connected to the rail and to extend from the sides thereof, an adjusting member operable through said clips and having an opening near one end, depending brackets connected to the adjusting member and equally spaced from one another, said brackets adapted to engage the ties to be spaced, and means connected to the end of the adjusting member to pull the same through the clips, and said means for operating the adjusting member comprising an anchor clamp adapted to be connected to the rail and having an opening, a cable and a ratchet device on the cable, said cable connected to the opening of the adjusting member and to the opening of anchor clamp respectively, said ratchet device being operable to effect a pull on the cable and upon the adjusting member.
